UNITED STATES PATENT OFFICE

JAMES G. GARRARD, OF GRAND RAPIDS, MICHIGAN, ASSIGNOR TO CHICAGO RAILWAY EQUIPMENT COMPANY, OF CHICAGO, ILLINOIS, A CORPORATION OF ILLINOIS

FOUNDRY LADLE

Application filed December 11, 1931. Serial No. 580,243.

This invention relates to ladles for use in transporting and pouring molten metal in foundries.

The main object of the invention is to provide a wheeled and pivoted ladle which may be stably supported in the rest position on the foundry floor without danger of accidental upsetting and which will be balanced substantially vertically above its supporting trunnions during transportation.

Another object is to provide a device of the above type in which the ladle is yieldingly supported in a manner to prevent slopping during conveyance from cupola to mold due to contact of the wheels with obstacles or irregularities in the foundry floor.

These and other detail objects are attained by the structure illustrated in the accompanying drawing, in which—

20 Figure 1 is a perspective view of the ladle in resting position.

Figure 2 is a side view of the same in transporting position, showing, in broken lines, the ladle in tilted position,

25 Figure 3 is a fragmentary end view, portions being sectioned for clearer illustration.

In the drawing, the ladle 1, of suitable shape and material for transporting and pouring molten metal, has a boss 2 at each side mounting a stationary spindle 3. Journaled on this spindle is a sleeve 4, having a transverse socket 5 receiving the spindle, and a longitudinal recess 6 housing a coiled spring 7. A band 16, surrounding the ladle, has a ladle manipulating bar 17 projecting rearwardly therefrom, the bar having a downwardly disposed end portion 18 for engaging the floor in the rest position of the device to stabilize the ladle.

40 The ladle is mounted on a tiltable carriage including a yoke 10, having trunnions 11 at each end within which axles 9 are rigidly secured by set screws 12, the axles mounting wheels 8 preferably on ball or roller bearing units. The yoke has a pocket 13 in which is secured the forward end of a forked handle 14 by means of bolt B. Projecting upwardly from each trunnion 11 is a standard 15 which extends into housing 4 and partially 45 through the coiled spring 7. The springs 7

serve to absorb shocks due to engagement of the wheels with obstacles during transportation and prevent slopping of the molten metal.

Handle 14 is disposed at an acute angle to standards 15 and forms a rigid unit therewith and with yoke 10. Obviously, the inclination of the standards will be controlled by the elevation of the handle 14 relative to the floor. In the rest position of the device, shown in Figure 1, with the forked ends of handle 14 lying on the floor, standards 15 will be inclined rearwardly from the vertical and the ladle supporting spindles 3 will be located rearwardly of trunnions 11. The weight of the ladle will then be balanced between wheels 8 and handle 14, and end portion 18 of the bar 17 will engage the floor and serve to stabilize the ladle.

During transportation the forked handle 70 14 will be raised by the workman, to the position shown in Figure 2, causing standards 15 to be disposed substantially vertically so that the weight of the ladle will be borne by wheels 8 alone through springs 7. In this 75 position, bar 17 rests in the crotch 19 of handle 14 to permit the ladle to balance on standards 15 and sleeves 4. The ladle may be readily tilted for pouring in either the rest position or in the upright position, the latter 80 being illustrated in broken lines in Figure 2.

All of the rigid connections and joints, except the connection of handle 14 with pocket 13, are preferably welded, but other means of joining may be utilized if desired. Moreover, the ladle might be mounted on a carriage having more than two wheels, in which case suitable framing would be provided arranged to tiltably mount the ladle supporting standards. No particular shape or size 90 of ladle is contemplated. The invention might be modified in these respects and others without departing from the spirit thereof, and exclusive use of all such modifications as come within the scope of the appended claims is contemplated.

What is claimed is:

1. In a conveying and pouring device, a carriage tiltably mounted on wheels, spaced standards and a handle rigid with said car- 100

riage, and a ladle pivoted on said standards above said carriage, said handle extending downwardly with its end engaging the floor, in the rest position of the device, and said standards being inclined from the vertical towards said handle in said position.

2. In a conveying and pouring device, a carriage tiltably mounted on wheels, spaced standards and a handle rigid with said carriage, and a ladle pivoted on said standards above said carriage, said standards supporting said ladle substantially vertically above the wheel hubs during transportation and being inclined from the vertical towards said handle in the rest position, said handle engaging the floor in said position to stabilize the ladle.

3. In a conveying and pouring device, a tilttable wheeled carriage, spaced standards and a handle rigid therewith, and a ladle yieldingly supported on said standards, said handle being elevated from the floor and said standards being disposed substantially vertically during transportation, and said handle engaging the floor and said standards being inclined towards said handle in the rest position of the device whereby the weight of said ladle will be balanced between the wheels and said handle in said latter position.

20 4. In a conveying and pouring device, a carriage including a yoke and wheels journaled at the ends thereof, transversely spaced standards and a handle rigid with said yoke, and a ladle pivoted on said standards, said handle engaging the floor in the rest position of the device, and being elevated from the floor during transportation, and said standards being disposed at an acute angle to said handle whereby said standards will be disposed substantially vertically during transportation and will be inclined towards said handle in the rest position.

45 5. In a conveying and pouring device, a tilttable wheeled carriage, spaced standards and a handle rigid therewith, and a ladle yieldingly supported on said standards, said standards being disposed substantially vertically and transmitting substantially all the weight of said ladle to the carriage wheels when said handle is elevated, and said standards being inclined rearwardly when said handle is lowered whereby the weight of said ladle will be divided between the carriage wheels and said handle.

55 6. In a conveying and pouring device, a tilttable wheeled carriage, a handle and spaced standards rigid therewith, said handle being disposed at an acute angle to said standards, a ladle pivoted on said standards, and a ladle tilting bar projecting from said ladle, said handle and bar being disposed to engage the floor in the rest position of the device and to cooperate in supporting and stabilizing said ladle in an upright position.

65 7. In a conveying and pouring device, a

wheeled carriage including a yoke having axle trunnions at the ends thereof, a standard projecting from each of said trunnions, a handle projecting from said yoke at an acute angle to said standards, a ladle yieldingly pivoted on said standards, and a ladle tilting bar projecting from said ladle above said handle and having a downwardly disposed portion, said handle and portion engaging the floor in the rest position of the device, and cooperating with the carriage wheels to support said ladle in an upright position.

70 8. In a conveying and pouring device, a tilttable wheeled carriage, spaced standards and a handle projecting therefrom, a ladle pivoted on said standards, and a ladle tilting bar projecting from said ladle above said handle, said handle and bar engaging the floor in the rest position of the device to stabilize the carriage and ladle, and said handle being elevated during transportation and supporting said bar to cause said ladle to balance on said standards.

80 9. In a conveying and pouring device, a tilttable wheeled carriage, spaced standards and a handle projecting therefrom, a ladle pivoted on said standards, and a ladle tilting bar projecting from said ladle, said handle extending downwardly and engaging the floor in the rest position to stabilize the carriage, and being elevated during transportation, and said bar engaging the floor in the rest position and resting on said handle during transportation to assist in maintaining said ladle in an upright position.

In testimony whereof I hereunto affix my signature this 7th day of December, 1931.

JAMES G. GARRARD.
